(57) **CLAIM**

The ornamental design for storage cabinet with wheels as shown and described.

DESCRIPTION

FIG. 1 is a front perspective view of the storage cabinet with wheels, showing our new design;

FIG. 2 is a front elevational view for the storage cabinet with wheels for FIG. 1;

FIG. 3 is a left-side elevational view of the storage cabinet with wheels of FIG. 1;

FIG. 4 is a right-side elevational view of the storage cabinet with wheels of FIG. 1;

FIG. 5 is a rear elevational view of the storage cabinet with wheels of FIG. 1;

FIG. 6 is a top plan view of the storage cabinet with wheels of FIG. 1; and,

FIG. 7 is a bottom plan view of the storage cabinet with wheels of FIG. 1.

The broken lines show portions of the storage cabinet with wheels that form no part of the claimed design.

1 Claim, 7 Drawing Sheets
